(57) **CLAIM**

The ornamental design for a hood and roof section for a car body, as shown and described.

DESCRIPTION

FIG. 1 is a front-right perspective view of the hood and roof section for a car body, showing my new design;

FIG. 2 is a rear-left perspective view thereof;

FIG. 3 is a right side view thereof;

FIG. 4 is a left side view thereof;

FIG. 5 is a top view thereof;

FIG. 6 is a bottom view thereof;

FIG. 7 is a front side view thereof; and,

FIG. 8 is a rear side view thereof.

The evenly broken line in the figure drawings represents unclaimed environment only and forms no part of the claimed design. The dash-dot broken line represents the boundaries and forms no part of the claimed design.
